(57) **CLAIM**

The ornamental design for a refrigerator, as shown and described.

DESCRIPTION

FIG. 1 is a perspective view of the refrigerator showing my new design;

FIG. 2 is a front elevation view thereof;

FIG. 3 is a left side elevation view thereof; and,

FIG. 4 is a right side elevation view thereof.

The broken lines in the drawing disclose the unclaimed portions of the refrigerator only and form no part of the claimed design.

1 Claim, 4 Drawing Sheets
